INDOOR TELEVISION RECEIVING ANTENNA

Margaret Kumpis and John B. Kumpis,
San Francisco, Calif.

Application October 7, 1954, Serial No. 32,571

Term of patent 7 years

(Cl. D26—14)

Figure 1 is a side elevational view of an indoor television receiving antenna, showing our new design;

Figure 2 is a front elevational view thereof; and

Figure 3 is a top plan view of Figure 2.

We claim:

The ornamental design for an indoor television receiving antenna, substantially as shown.
